UNITED STATES PATENT OFFICE.

FREDERICK GEORGE WINKLER, OF BUFFALO, NEW YORK, ASSIGNOR, BY MESNE ASSIGNMENTS, TO BEREND J. BURNS AND CLIFFORD A. CUTLER, BOTH OF BUFFALO, NEW YORK.

SPRING.

1,074,582.

Specification of Letters Patent. Patented Sept. 30, 1913.

Application filed October 29, 1907. Serial No. 399,759.

To all whom it may concern:

Be it known that I, FREDERICK GEORGE WINKLER, a citizen of the United States, residing at Buffalo, in the county of Erie and 5 State of New York, have invented new and useful Improvements in Springs, of which the following is a full, clear, and exact specification.

My invention relates to springs, and is 10 generally adaptable for use wherever it is desired to control the intensity of the resistance to the load in a predetermined way.

In making my invention, I have sought to produce such a spring as would give, when 15 subjected to a variable load, a gradually increasing ratio of resistance and in addition to that, to produce such a spring as would enable me to predetermine and govern the 20 intensity and increase or decrease of the resistance of the spring when it shall be subjected to a load.

As is well known the springs of the prior art have been such that their resistance to loads have been entirely incapable of control 25 and such resistance has been one that has increased regularly from the start to the limit of its action and most of such springs, as they have reached their limit of action, have shown a lessening of their progressive increase 30 of resistance. It is a well known characteristic of such springs that when subjected to a gradually increasing load, their resistance increases regularly in approximately an arithmetical progression up to a certain 35 limit and after a certain limit is reached, such progressive increase becomes rapidly less until the limit of resistance is finally reached. This characteristic of that form of springs heretofore in use which are known 40 as leaf spring, is somewhat modified by the friction produced by the sliding of the leaves during the time that they are acted on by the load. This practically universal characteristic of springs of the prior art has been 45 one inherent in the springs and one that could not be controlled or changed in any known practical way.

My springs herein described, are of such a character that I am able to predetermine not 50 only the rate of progressive increase of spring resistance to a load, but also to determine the nature of that progressive increase. That is to say I am able to produce a spring which may at the will of its maker be given 55 a characteristic such that when subjected to

a load, its increase of resistance to that load may be first substantially an arithmetical increase and later a geometrical increase and after a certain limit is reached (which limit may be predetermined), it may have as desired either a greater or a less geometrical increase or such geometrical increase may be changed in such a way that it gradually approaches an arithmetical increase of resisting power.

In order to make my explanation a little clearer, I will illustrate what I mean by the increase of spring resisting power by the following illustration:—Thus, if the springs of the prior art were subjected to an initial 70 load which compressed them one unit of distance, then twice the amount of the initial load would be necessary to compress them through the second unit of distance and three times the amount of the initial load to 75 compress them through the third unit of distance and four times the amount of the initial load to compress them through the fourth unit of distance. After a certain limit is reached, say at seven times the 80 amount of the initial load, the resisting power of the springs may have decreased so that such application of load at that limit would compress the springs through a greater unit of distance than the previously increased load compressed them.

Comparing the compression of my springs with those of the prior art, the following example will serve to show what I mean by a geometrical increase of spring resisting power: Thus if a unit of load is applied to my spring at the beginning it will compress it through a unit of distance; if the initial unit of load is doubled, it will compress my spring through its second unit of distance; it would be necessary to quadruple the initial load which is applied to my spring to compress it through its third unit of distance; and it would require eight times the amount of initial load to compress my spring through a fourth unit of distance; 90 through a fifth unit of distance and sixteen times the amount of initial load to compress the spring through a fifth unit of distance. These rates of increasing the amount of load would increase substantially according to a continual doubling up of the previous load in a regular geometrical increase. This rule, however, is subject to variations as may be desired, and it is always under the control of the makers of the spring since 130

they are able to control the strength of the spring parts, their curve formation, their tension and their resisting power.

For the purpose of more particularly describing and illustrating my invention, I will make reference to the drawings consisting of one sheet and eleven figures in which like characters of reference indicate corresponding parts throughout the several views.

10 Figure 1 shows a typical illustration of one of my springs wherein the resisting power increases in a geometrical progression. Fig. 2 is an illustration of one of my springs wherein the resisting power increases in a geometrical ratio up to a certain limit and then gradually lessens the rapidity of its increase. Fig. 3 is an illustration of one of my springs wherein the resisting power of the spring increases according to a geometrical progression up to a certain limit and then at that limit lessens its progressive increase much more rapidly than the form of spring shown in Fig. 2. Fig. 4 is another modification of my invention wherein the resisting power starts with a substantially arithmetical increase of resistance and after it has reached a certain limit its resisting power rapidly increases substantially in a geometrical ratio. Fig. 5 shows another modification of my invention wherein the resisting power increases in substantially an arithmetical progression up to a certain limit and then it approaches a geometrical progression but later that is somewhat modified by the combined action of the several parts of the spring. Fig. 6 shows a further modification of my invention wherein its resisting power initially substantially approaches a geometrical ratio of increase, and 40 then at a predetermined limit assumes approximately an arithmetical ratio of increase. Fig. 7 shows a further modification of my invention wherein its resisting power increases substantially according to an arithmetical ratio until a predetermined limit is reached, when it increases substantially in a geometrical ratio until a predetermined limit is reached when it again changes until it increases again substantially according to 50 an arithmetical ratio. Fig. 8 shows a construction having four pivotal points. Fig. 9 shows a spring which is a modification of that shown in Fig. 7. Fig. 10 illustrates a spring where the point of application of the load is changed from the point shown in the other views. Fig. 11 shows a still different place and means for applying the load.

It will be noted that in these various views, my springs are shown as combinations of a number of simple springs; in other words, they are compound springs made up of a number of simple springs and in Figs. 1, 2, 3, 4, 5 and 10, they are shown as made up of two mechanical parts riveted or united in 65 any other suitable way.

In Figs. 1, 2, 3, 4, 5, 6, 8, 10 and 11, I have employed the curve or wave formed part 10. This wave formed part 10 is united in Fig. 1, with a compound curved part 11. When a load is applied to the spring illustrated in Fig. 1 at the point marked 12 in the wave formed part 10 the spring may be secured at the point marked 13 in the curved part 11 and the tendency of the load so applied is immediately to put the wave formed part 10 under ever increasing tension and stretches it so that its waves are gradually flattened. Simultaneously with the flattening of the wave formed part 10, is an ever increasing tension which draws the ends 14 toward the plane passing through points 12 and 13. As soon as the ends 14 move toward the plane passing through the points 12 and 13 and consequently toward each other, the tendency is to straighten out the curves of the curved part 11 and thereby place such part 11 under a constantly increasing compression which will become more intense according as the angles produced at the joining of the parts 10 and 11 with the points 14 become more and more acute. Thus it will be evident that when a load is applied to a spring of the character illustrated in Fig. 1, simultaneously with the bending of the parts of the spring, there is a compression of the part 11 and a tension of the part 10. Thus the part 10 approaches its limit of tension while the part 11 approaches its limit of compressibility and allows a compression of such character that the points 12 and 13 may be prevented from ever coming in contact with each other since the limit of approach can be governed by the tensile strength of the material used.

The spring illustrated in Fig. 1 is more especially adaptable for those uses in which the loads carried by it are very changeable such as for freight cars, trucks or other similar uses. The central portion of the wave formed part 10 where the load is applied and the central portion of the curved part 11 where the spring is fixed to the body carrying it, are preferably reinforced or strengthened by a greater quantity of metal in order to give to those parts the requisite degree of strength desired. The ability to reinforce and strengthen these parts of my spring, which in other springs are necessarily always weak, is one of the distinguishing characteristics of my invention.

It is apparent that the movable point 12 and the fixed point 13 in the various constructions shown may be reversed according as convenience may dictate.

In Fig. 2 the wave formed part 10 is substantially the same as the part 10 in Fig. 1 and is united by means of a pivot or other suitable means to a part 16 which is differentiated from the part 11 in Fig. 1 by a curved neck 17 that is bent inwardly at both 130

ends toward the end of the wave formed part 10. In this construction if the load is applied at the movable point 12 its first tendency is a slight bending and simultaneously tends to straighten out and bring under tension the wave portion 10 and that will be substantially the only effect produced by the action of the spring until a certain limit is reached when the increased load will have reached a certain tensile resistance of the wave formed part 10 when the neck portions 17 of the curved part 16, will be drawn slightly inwardly. As soon as this point of action is reached, a certain leverage is produced by means of the neck portion 17 which tends to straighten out the curve of the part 16 and to curve it slightly oppositely; in other words, it puts the part 16 under compression. The leverage produced by the part 17 causes a slighter degree of resistance than is produced by the acute angle leverage formed at the points 14 in Fig. 1. When the load is thus applied in Fig. 2, the results of its application will be substantially the same as heretofore described in relation to Fig. 1 except that the progressive increase is modified by the leverage produced at the point 17 and thus the geometrical ratio of increase is lessened, and especially so, soon after the part 16 has lost its original curved formation. It will be apparent that the construction shown in Fig. 2, is more particularly adaptable for those uses where the load is not a very changeable load as for example in automobile carriages and passenger coaches.

In Fig. 3 a construction is shown which is practically identical with that illustrated in Fig. 2 except that the neck portions 17 are increased in size with the result that a still greater leverage is produced until the curved part 16 is straightened out and slightly bent oppositely and thereby the increase of resisting power is diminished to a greater degree than would be the case with the construction shown in Fig. 2.

In Fig. 4 the part 10 is identical with the part 10 of Fig. 1 and the part 18 is identical with the part 11 of Fig. 1 except that it is provided with a downwardly bending bill 19 which is secured in a suitable manner to the part 10 and is made a part of the curved portion 18. In this construction the resisting power of the spring increases gently for a longer time at the start than does the resisting power of the construction shown in Fig. 1 until it reaches a limit when the union 20 approaches closely to a contiguous part of the curved portion 18 and the angles becoming very acute, the resisting power rapidly increases to substantially the same as that of Fig. 1.

The construction in Fig. 5 is substantially identical with that shown in Fig. 4, except that the bill portions 19 are greater than

those shown in Fig. 4 with the effect that the period of the gentle increase of resisting power is lengthened over that described concerning the spring shown in Fig. 4.

It will be apparent that the resisting power of these various constructions of springs shown, will be governed largely by the amount and character of metal used in the various parts of the springs.

In Fig. 6 the same wave formed part 10 is used in combination with two spiral form parts 21 and 22. The load is applied at the point marked 12. The fixed points of the springs are at the centers of the spirals 23 and 24 which may be secured rigidly to the body carrying the spring. From the description of the constructions heretofore given, it will be apparent that when load is applied at the point marked 12, the first result will be to straighten out the weaker and more sensitive parts of the spring and thus produce a gentle start and a succeeding rapid increase of resisting power substantially according to a geometrical ratio until it reaches a certain limit when the weight of the load calls into play the resisting action of the stronger parts of the spiral springs 21 and 22 and when this effect is produced, the resisting power of the springs will approach an arithmetical ratio of increase. This form of spring is more particularly applicable for those uses where a half elliptical spring is used or where a truss would be needed to support the center of the car.

In Fig. 7 a construction is shown similar to that shown in Fig. 6 except that in place of the wave formed part 10, is substituted either a straight line part 25 or a concave part 26 either of which parts may be united in a suitable manner to the spiral portions 21 and 22. It will be evident that as soon as a load is applied at the point 12 of the straight line part 25, its immediate effect will be to call into play the spirals 21 and 22 instead of calling them into action at a later stage as they would be in the construction shown in Fig. 6. When the concave part 26 is used, the first action of the load when it is applied at the point 12 will be to produce an arithmetical increase of resistance at first until the part 26 assumes approximately (or has passed) a straight line when the load will call into greater play the spiral springs 21 and 22 and then the action of the spring will be substantially identical with the action produced when the part 25 is used with the spiral springs 21 and 22.

It will be apparent that any of the fixed solid parts of the curved portions 11, 15, and 18 can be cut away and the same results effected as though constructed as shown in the first five figures. The rigid frame of the car or body to which the spring is attached would then represent such cut out portions.

In Fig. 8 is shown a diamond shaped con-

struction which has four pivotal points at 29, 30, 31 and 32. At the pivotal point 30 the load may be applied and at 32 the spring may be fixed to the frame of the body carrying it or vice versa. This construction would be likewise practical even though it had but three pivotal points since for one, say point 31, there could be substituted a goose-neck similar for example to that shown in Fig. 3. Uniting the four sides of the diamond are wave formed parts 33 and these wave formed parts may be increased or diminished in quantity or strength at will. It will be likewise evident that the same wave part may be made of greater strength in one portion than in another for the purpose of furnishing a more variable resistance to the load. Obviously when a load is applied at the point 30 beginning with a gentle initial resistance, it will meet with a rapidly increasing resistance as the spring is compressed. When the weight of the load has thrown the points 30 and 32 closely together, then if the wave formed portions do approach the limit of their stretching capacity and therefore approach a tensile strain they will give a greater resistance to the load, but if none of such wave formed portions approach the limit of their stretching capacities, the load resisting power of the spring will rapidly diminish. Thus at the beginning of the application of the load for each unit of compression, there will be a comparative large movement of the parts 29 and 31. As the weight of the load increases and when the points 30 and 32 have traveled through a unit of distance, the points 29 and 31 will travel only a small part of their initial travel.

Fig. 9 represents a construction which is a modification of the spring illustrated in Fig. 7 in that the straight portion 25 is made in two parts 34 and 35 which are pivoted at the point 36. When the load is applied to this spring at the point 36 there will be a very gentle movement of the parts 34 and 35 which will not afford great resistance to the load since the motion of the parts of the spring at the start is mainly only a gentle bending of the spiral elements. As the weight of the load increases, there results immediately a tensile strain upon the parts 34 and 35 in addition to the bending above referred to and thus a greater resistance is offered to the load and this increase of tension will increase as the load increases in substantially a geometrical progression up to the limit of the tensile power of the weaker parts of the spring. If the spiral 37 be made stronger than the spiral 38 or oppositely, the travel of the point 36, where the load is applied, will be away from a perpendicular to that point and such variance from the perpendicular will depend on

the respective difference of strength between the spirals 37 and 38. Such movement from the center could also be produced by placing at the application point 36 of the load a lever which would direct the travel of the said application point in any desired path. Thus it is evident that the travel of the application point of the load may be governed in any predetermined way that it is desired without in any way interfering with the action of the spring. Obviously the variation of strength of the parts of the spring as illustrated in Fig. 9 may be made regulatable by winding the spiral up and thus increasing its tension.

The spring shown in Fig. 10 is a modification of some of the other constructions herein illustrated and shows how I am able to change the point of application of the load and still preserve the peculiar action of my spring. Thus normally the point of application in this spring would be at 39, were all its parts constructed, so far as strength is concerned, in like manner to those shown in Figs. 1, 2, 3, 4 and 5. If, however, the strength of the part 40 is increased as shown at 41 the point of application of the load may be changed toward or to point 42 and still the action of the spring be preserved as hereinbefore described so that when the load is applied at the point 42, the tendency of travel of the said point will be in a curved line, such curve being controlled by the stretching of the wave formed part 10 against the resistance of the reinforced part 41 and it will be likewise affected by the straightening out of the weaker end of the part 40 as it stretches out toward a straight line.

Fig. 11 illustrates a modification of the spring shown in Fig. 10 wherein I have connected the reinforced part 41 with a lever 43 pivoted at the points 44 and 45. The point of application of load is at 45. In this construction when the load is applied, the travel of the point 45 will be on a curved line which will be governed by the straightening out of the wave formed part 10 which acts against the resistance of the reinforced part 41 solely. The introduction of the lever 43 controls the guiding action such as is produced by the weaker end of the part 40 and thus allows the load application point 45 to travel in any predetermined direction. Obviously the point 45 of the load application might be changed either outwardly, inwardly or in any other direction than that shown without departing from the principle of operation above described. It is likewise obvious that instead of the curved part 41 there could be substituted a spiral or any other suitable reinforced or strengthened part.

A greater power and a more rapid increase of resistance may be given to any

or all of the constructions shown in the various figures if the parts united by the wave formed parts 10 are initially bent or put under tension when united to the other portions of the springs. It should be noted that whatever the variation in the tension of the parts of my springs may be, such variation influences very slightly the initial resisting power of the spring but it very largely increases the subsequent progressive increased resistance of the spring.

It is apparent that my invention consists of a principle which as applied to springs is capable of numerous adaptations and variations in form and construction and I do not wish to be confined to the examples illustrated and described.

Having thus described my invention and its method of operation, what I claim is:

1. A compound spring comprising bending and stretching portions the bending portion or portions being so arranged that they will respond in a substantially arithmetical progression of resisting power against the pressure of the load, and the stretching portion or portions being so arranged in combination with the bending portion or portions that the said arithmetical progressive action will be modified into a progressive geometrical resistance against the load.

2. A compound spring comprising bending and stretching portions the stretching portion or portions being so arranged that they will respond in a substantially geometrical progression of resisting power against the pressure of the load and the bending portion or portions being so arranged in combination with the stretching portion or portions that the said geometrical progressive action will be modified in its progressive action.

3. A compound spring comprising two or more bending portions so combined and arranged that one or more of said portions when under load will respond in a substantially arithmetical progressive resisting power to the pressure of the load by bending and gradually be brought to a tensile resistance against one or more other and stronger of the said bending portions of the spring thereby modifying said arithmetical progressive resisting power into a substantially geometrical progressive resisting power.

4. A compound spring comprising two or more bending and stretching portions so arranged that when under a load one or more of said portions will respond to the action of the load by simultaneously bending and stretching in combination with the other of said portions which will respond simultaneously with the first of said portions by bending and compressing, and being so arranged that any desired modification in the

progressive increase of resistance against the load may be obtained.

5. A compound spring comprising two or more bending and stretching portions so arranged that when under a load one or more of said portions will respond to the action of the load by stretching in combination with the other of said portions which will respond simultaneously with the first of said portions by bending and compressing, and being so arranged that any desired modification in the progressive increase of resistance against the load may be obtained.

6. A compound spring comprising two or more bending and stretching portions so arranged that when under a load one or more of said portions will respond first in a substantially arithmetical progression of resisting power against the pressure of the load and then will respond to the action of said load by simultaneously bending and stretching in combination with the other of said portions which will respond simultaneously with the first of said portions by bending and compressing thereby modifying said arithmetical progressive resisting power into a substantially geometrical progressive resisting power.

7. A compound spring comprising two or more bending and stretching portions so arranged that when under a load one or more of said portions will respond first in a substantially arithmetical progression of resisting power against the pressure of the load and then will respond to the action of said load by simultaneously bending and stretching in combination with the other of said portions which will respond simultaneously with the first of said portions by bending and compressing thereby modifying said arithmetical progressive resisting power into a substantially geometrical progressive resisting power in combination with the comparatively stronger bending portions under the progressive action of the load will further modify said resisting power and lessen it in its progressive geometrical action.

8. A compound spring comprising bending and stretching portions and connecting means between the same, the bending portion or portions being so arranged that they will respond in a substantially arithmetical progression of resisting power against the pressure of the load, the stretching portion or portions being so arranged in combination with the bending portion or portions that the said arithmetical or progressive action will be modified into a progressive geometrical resistance against the load, and all of the said parts being so combined and arranged that before they are placed under a load one or more of said bending portions will be placed under an elastic tension.

9. A compound spring comprising bend-

the said parts being so combined and arranged that before they are placed under a load one or more of said bending portions will be placed under an elastic tension, and 5 also so combined and arranged that when a load is applied one or more of said portions will respond to the action of the load by stretching and another of said portions will

respond simultaneously with the first of said portions by bending and compressing. 10

In witness whereof I have hereunto set my hand in the presence of two witnesses.

F. GEORGE WINKLER.
